CLAIM

The ornamental design for a case for personal belongings as shown and described.

DESCRIPTION

FIG. 1 is a front perspective view of the case for personal belongings showing my design;

FIG. 2 is a rear perspective view thereof;

FIG. 3 is a front elevation view thereof;

FIG. 4 is a left side view thereof;

FIG. 5 is a rear elevation view thereof;

FIG. 6 is a top plan view thereof;

FIG. 7 is a bottom view thereof; and,

FIG. 8 is a right-side view thereof.

Portions of the case for personal belongings shown in broken lines are for the purpose of illustrating stitching or portions of the case that form no part of the claimed design.

1 Claim, 8 Drawing Sheets
